UNITED STATES PATENT OFFICE.

CHARLES B. VER VALEN, OF CENTRALIA, WASHINGTON, ASSIGNOR OF ONE-HALF TO
T. CAMPBELL BLACK, OF PORTLAND, OREGON.

HOOK.

Application filed September 22, 1925. Serial No. 57,892.

The object of the present invention is to provide a hook-like device which may be used in hoisting and other similar operations and will prevent members engaged therewith from slipping therefrom.

A very particular object of the invention is to provide a hook-like device of this nature which is exceedingly simple in its construction, strong, durable, reliable, and efficient in use, easy to manipulate, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

20 In the drawing,

Figure 1 is a sectional elevation of the device embodying the features of my invention.

Fig. 2 is an edge elevation thereof, and Fig. 3 is a detail view partly in section taken substantially on the line 3—3 of Fig. 2.

Referring to the drawing in detail, it will be seen that 1 designates a shank which has a hook extension 2 at one end while the other end thereof is reduced as at 3 has swivelly engaged thereon an eye 4. The reduced portion 3 is threaded intermediate its ends as at 5 and below the threaded portion 5 is provided with a notch or recess 6.

A lock arm 7 has a bifurcated end 8 adapted to straddle the reduced terminal 9 of the hook extension 2 and to be pierced by pivot pin 10 extending through said reduced terminal 9. As is shown in Fig. 3, the reduced end or terminal 9 of the hook extension 2 is preferably separable therefrom being engaged rigidly in place by suitable fastening elements 11. The free end of the lock arm 7 is reduced as is indicated at 12 and said reduced end 12 is adapted to be received in the notch or recess 6 when the lock arm is closed as is shown in Fig. 1. This reduced end 12 forms a shoulder 13 with the arm 7. The reduced portion 3 of the shank 1 formed therewith an annular shoulder 14 which has a portion cut away which will be supplied by the shoulder 13 when the arm 7 is in a closed position.

A sleeve 15 has the upper interior portion 55 thereof threaded as is indicated at 16. This sleeve is disposed about the reduced portion for engagement with the threads 5. By screwing downwardly on this sleeve 15 it will be seen that the sleeve may be extended 60 over the reduced portion 12 of the arm 7 when in a closed position, thereby locking said arm in said closed position.

From the above detailed description, it will be seen that this hook-like device prevents objects such as a sling or the like which is engaged with the hook extension 2 from being accidentally or otherwise removed therefrom when the lock arm is closed.

It will also be seen that the sling will still be maintained in engagement with the device even though the arm 7 is open and in order to disengage the sling or the like it must be lifted over the end of said hook extension 2.

The construction, operation, utility, and advantages of this invention should now be clearly understood without a more detailed description thereof. It is apparent that changes in the details of construction may be resorted to without departing from the spirit or scope of the invention as herein-after claimed or sacrificing any of its advantages.

Having thus described my invention, what I claim as new is—

A device of the class described including a shank having a hook extension at one end and having its other end reduced and provided with an intermediately threaded portion and a notch between the threaded portion and the shank proper, a shoulder extending partially about the juncture of the reduced end and the shank proper, a sleeve 90 threadedly engaged with said threads and movable over the notch, and a lock arm pivoted on the terminal of the hook extension having its free end reduced to form a shoulder and engageable in said notch to be locked therein by said sleeve and so that the second shoulder aligns with the first shoulder to form an annular abutment thereabout for the sleeve to limit the movement of the said sleeve.

In testimony whereof I affix my signature.

CHARLES B. VER VALEN.
